UNITED STATES PATENT OFFICE.

SHERMAN SMITH, OF PITTSBURGH, PENNSYLVANIA, ASSIGNOR TO STANDARD SANITARY MANUFACTURING COMPANY, OF PITTSBURGH, PENNSYLVANIA, A CORPORATION OF NEW JERSEY.

DESIGN FOR A COMBINED VALVE HANDLE AND HOUSING.

Application filed February 21, 1928. Serial No. 25,500. Term of patent 14 years

To all whom it may concern:

Be it known that I, SHERMAN SMITH, a citizen of the United States, and residing at Pittsburgh, in the county of Allegheny and State of Pennsylvania, have invented a new, original, and ornamental Design for a Combined Valve Handle and Housing, of which the following is a specification, reference being had to the accompanying drawing,

forming a part thereof, which shows a perspective view of the article showing my new design.

I claim:

The ornamental design for a combined valve handle and housing, substantially as shown.

SHERMAN SMITH.
